UNITED STATES PATENT OFFICE.

FRANK A. SHARPNECK AND LEE O. GILLILAND, OF CHICAGO, ILLINOIS; SAID SHARPNECK ASSIGNOR TO SAID GILLILAND.

INTERNAL-COMBUSTION ENGINE.

1,140,292.

Specification of Letters Patent. Patented May 18, 1915.

Application filed November 10, 1913. Serial No. 800,057.

To all whom it may concern:

Be it known that we, FRANK A. SHARPNECK and LEE O. GILLILAND, citizens of the United States, residing at Chicago, county of Cook, State of Illinois, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

Our invention has for its principal object to produce an internal combustion engine in which the piston shall receive a plurality of successive power impulses so as to give a more uniform pressure throughout the working stroke than in the ordinary engine.

A further object of our invention is to produce a novel form of internal combustion engine which shall be simple and compact in construction and be capable of producing great power.

The various features of novelty whereby our invention is characterized will hereinafter be pointed out with particularity in the claim; but for a full understanding of our invention and of its objects and advantages, reference may be had to the following detailed description taken in connection with the accompanying drawings, wherein:

Figure 1 is a section taken at right angles to the axis of an engine arranged in accordance with one form of our invention, the section being taken approximately on line 1—1 of Fig. 6; Fig. 2 is a section on line 2—2 of Fig. 1; Fig. 3 is a side view of the intake casting with the cover removed; Fig. 4 is a detail showing the circuit closing device; Fig. 5 is a view looking toward the left from the left hand side of Fig. 4; Fig. 6 is a section taken approximately on line 6—6 of Fig. 1; and Fig. 7 is a section taken approximately on line 7—7 of Fig. 6.

In the drawings we have illustrated our invention as embodied in a double acting engine having a stationary casing and a rotary crank shaft. It will of course be understood that our invention is not limited to this particular form of engine but may be embodied in any other desired type.

Referring to the drawings, 1 is a closed casing substantially cylindrical in form and

having on one side a flange, 2, to form the supporting base. The casing may conveniently be made in two halves divided on a plane at right angles to its axis and having suitable engaging flanges which may be fastened together by studs or bolts, 4. The walls, both the cylindrical walls and the end walls, of the casing are made hollow so as to provide a series of chambers separated from each other. The interior of the casing is bored out so as to form the cylinder, 5, of an engine. One of the chambers, 6, extends throughout the entire length of the cylinder and communicates at opposite ends with the opposite ends of the cylinder through openings, 7 and 8. Another chamber, 9, on the opposite side of the casing communicates with the interior of the cylinder through ports, 10 and 11, spaced apart from the ends of the cylinder and closed by suitable outwardly opening check valves, 12. A third chamber, 13, arranged preferably just beside the chamber 6 and having no communication with the latter chamber, communicates with the interior of the cylinder through ports, 14 and 15, entering the cylinder between the ends and the transverse planes passing through the ports 10 and 11. The remaining chambers, 16 and 17, serve to contain water or any other suitable cooling means which will keep the walls and heads of the cylinder cool.

Extending transversely through the cylinder, midway between the ends thereof is a crankshaft, 20. In the opposite ends of the cylinder are pistons, 21 and 22, respectively, each being connected to the crank shaft by a suitable connecting rod, 23. The parts are preferably so proportioned that the diameter of the pistons is greater than the length of stroke so as to permit the structure to be made short and compact.

Each of the chambers 6 and 13 is provided with an inlet valve, 25, through which a combustible charge may be drawn. In the arrangement shown, the two valves 25 are arranged in a single casing, 26, into which opens a supply pipe, 27, thus permitting both of the chambers 6 and 13 to be supplied with a combustible mixture through a single pipe. In the chamber 26 there is also a suitable exhaust valve, 30, adapted to be actuated by a cam lever mechanism, 31, driven in any suitable way from the crankshaft so as to cause the valve to be opened when the

pistons approach the ends of their exhaust strokes. The chamber 6 is provided with a spark plug, 35, or other suitable igniting device and, if desired a similar device may be employed in connection with the chamber 13. The current to the ignition device or devices may be controlled by any suitable timing mechanism illustrated conventionally at 36. The chamber 9 opens to atmosphere through a port, 37, which may lead directly to atmosphere or to a suitable exhaust pipe.

The operation is as follows: Assuming the pistons to be moving toward each other on a suction stroke, the combustible mixture will be drawn into both the chambers 6 and 13 and will pass through the ports 7, 8, 14 and 15 into the cylinders. On the return stroke of the pistons the charge in the chamber 13 will be compressed until the pistons pass the ports 14 and 15 and thereafter only that portion of the charge contained in the cylinder and in the chamber 6 will be compressed. As the pistons start on their return stroke, or working stroke, the compressed charge in the chamber 6 will be fired and give a power impulse to the pistons. When the pistons uncover the ports 14 and 15, the charge contained in the chamber 13 will be ignited by the hot gases in the cylinder and a second power impulse will be given to the pistons. We have found that the ignition of the auxiliary charge by the hot gases in the cylinder actually takes place and therefore no independent igniting device need be placed in the chamber 13, unless desired. It will be seen that the second power impulse is brought to bear on the pistons after the pressure in the cylinder has been reduced somewhat, but before an extreme low pressure has been reached and consequently the pressure throughout the remainder of the working stroke will never fall as low as in the ordinary single impulse engine. Just before the pistons reach the end of their working stroke, the ports 10

and 11 are uncovered and the combustion gases are exhausted through these ports. The relief valve, 30, is now opened so that upon the exhaust stroke of the pistons, 50 the combustion gases remaining in the cylinder are forced out through the valve 30. On the next stroke, which is the suction stroke, the cycle will begin to repeat itself. 55

While we have illustrated and described only a single successful form of engine embodying our invention and one in which only two successive power impulses are given to a piston, we do not desire to limit ourselves to any particular form of engine 60 or to any particular number of successive power impulses; but intend to cover all forms and arrangements and any desired number of successive power impulses as will be apparent from the terms employed in the 65 definitions of our invention, constituting the appended claim.

We claim:

In an internal combustion engine, a cylinder and a piston reciprocable relative to each other, a combustion chamber in open communication with the compression end of the cylinder, a second combustion chamber shut off entirely from the first combustion chamber having a passage leading into the 75 cylinder at such a point that it would be covered by the piston when the latter is at the beginning of its working stroke and be uncovered by the piston after the latter has partially completed its working stroke, 80 means for admitting a combustible mixture directly into each of said chambers, and means for igniting the combustible mixture in each of the combustion chambers.

In testimony whereof, we sign this specification in the presence of two witnesses.

FRANK A. SHARPNECK.
LEE O. GILLILAND.
